(57) **CLAIM**

The ornamental design for a decorative film as shown and described.

DESCRIPTION

FIG. 1 is a perspective view of the first embodiment of a decorative film showing the claimed design;

FIG. 2 is a front view thereof;

FIG. 3 is a back view thereof;

FIG. 4 is a left side view thereof, the right side view being a mirror image of the left side view;

FIG. 5 is a top side view thereof, the bottom side being a mirror image of the top side view;

FIG. 6 is an enlarged detail view of area 6 in FIG. 2;

FIG. 7 is an enlarged detail view of area 7 in FIG. 2;

FIG. 8 is an enlarged detail view of area 8 in FIG. 2;

FIG. 9 is an enlarged detail view of area 9 in FIG. 2; and
FIG. 10 is an enlarged detail view of area 10 in FIG. 2.

FIG. 11 is a perspective view of the second embodiment of a decorative film showing the claimed design;

FIG. 12 is a front view thereof;

FIG. 13 is a back view thereof;

FIG. 14 is a left side view thereof, the right side view being a mirror image of the left side view;

FIG. 15 is a top side view thereof, the bottom side being a mirror image of the top side view;

FIG. 16 is an enlarged detail view of area 16 in FIG. 12;

FIG. 17 is an enlarged detail view of area 17 in FIG. 12;

FIG. 18 is an enlarged detail view of area 18 in FIG. 12;

FIG. 19 is an enlarged detail view of area 19 in FIG. 12; and,
FIG. 20 is an enlarged detail view of area 20 in FIG. 12.

The outer broken lines in FIGS. 1-5 show boundaries of the decorative film for illustrative purposes only and form no part of the claimed design. The dot-dash-dot broken lines in FIG. 2 that mark areas 6-10, in FIG. 12 that mark areas

(Continued)

16-20, and in FIGS. 6-10 and FIGS. 16-20 that circumscribe the views are used to indicate boundaries of the respective areas and enlarged detail views, and these dot-dash-dot broken lines form no part of the claimed design.

1 Claim, 16 Drawing Sheets
